UNITED STATES PATENT OFFICE

WILLIAM L. VALIQUETTE, OF DAYTON, OHIO, ASSIGNOR TO THE HARRIS-SEYBOLD-POTTER COMPANY, OF DAYTON, OHIO, A CORPORATION OF DELAWARE

CLAMP FOR PAPER CUTTERS

Application filed May 11, 1927. Serial No. 190,579.

My improvements relate to the construction and operation of a supplemental clamping device or paper leveler to be used in connection with the clamp mechanism of paper cutters such, for example, as is shown in the Seybold Patent No. 1,451,120. The object of the invention is to provide a clamp plate which shall extend over practically the entire surface of the paper pile for use with light and fluffy papers which ordinarily do not lie flat and when the package is adjusted against the back gauge and clamped with the ordinary, somewhat narrow clamp along the cutting edge, the pile is apt to be disturbed and the sheets when cut will not be of uniform width or length owing to the uneven character of the paper pile.

The invention consists of that certain novel construction and arrangement of parts to be hereinafter more particularly pointed out and claimed in which a grid is provided to cover the entire pile of paper with mechanism for operating same in timed relation to the operation of the clamp but independent of the clamp.

In the drawings:—

Figure 1 is a side elevation illustrating my improvements.

Figure 2 is a plan view of the same.

Figure 3 is a detail end view of the outer right hand corner of the device.

In the drawings I have only illustrated the table portion of any ordinary paper cutting machine in detail, only certain elements of the clamp and clamp operating mechanism being indicated as such mechanism is shown in detail in the Seybold Patent No. 1,451,120 heretofore referred to.

The table is shown at 1 supported on the frame of the machine with the side standards 2—2 broken away. Secured along each side of the table at the rear of the clamp 3, are side bars 4—4, between which is mounted a grid frame made up of vertically disposed metallic bars 5—5, bolted at the ends to cross bars 6—6, so as to form a substantial rectangular frame.

In order to support the frame for vertical movement parallel to the table, I employ bell crank levers 7, 7. To the ends of the hori-

zontal arms of these levers the frame is secured by studs 7a, 7a projecting from the frame. The pivots of the bell crank levers are provided with flanged rollers 8, 8 which ride on bridges 9, 9 on the side bars 4.

55

The depending arms 10, 10 of the bell cranks are connected together by links 11, whereby a movement parallel to the table is obtained.

To guide the grid frame vertically the studs 7a, 7a for the outer end of the grid are secured to boxes 12, which slide vertically in guide ways 13, formed in the side bars 4.

As the pressure frame or leveler is moved, the flanged rollers 8, 8 ride on the surface of the bridges 9 to permit the movement of the parts.

Secured to each end of the shaft 12a extending transverse and underneath the table and mounted in the depending portion of the side bars 4 is an arm or lever 13a, one for each end of the shaft, which arms 13a are connected by a short link 14, with the upper arm 15 of a T-shaped lever 15a, the central arm of which is connected to the cross bar 6.

75

The shaft 12a is rocked by a trigger arm 16 secured to the shaft 12a, which is engaged by a roller or stud 17 on a gear 18 mounted in the frame. This gear 18 is driven by a train of gearing shown in dotted lines in Figure 1 from a driving gear 19 on the driving shaft.

The gear 18 has an eccentrically arranged post 18a to which eccentric strap 18b is connected. The strap 18b has a yoked end 18c which engages a pin 18d on the clamp bar 3.

85

This mechanical driving connection is similar to that shown in the Seybold Patent No. 1,504,521. The gearing train is so timed that when the clamp 3 is in raised position, the roller 17 will be in contact with the trigger arm 16 as indicated in Figure 1. While in

that position the grid frame will be supported over the table in raised position. As the main clamp 3 is brought down to the paper pile, the roller 17 is withdrawn from contact with the trigger arm, the gear 18 rotating in clockwise direction; this releases the grid

or paper leveler and the grid drops to the paper pile by gravity thus smoothing out and leveling the paper.

100

In order that the grid shall not interfere with the back gauge 20, the back gauge is provided with slots 21 to permit the vertical bars of the paper leveler to descend without interference in whatever position the back gauge may be located. The back gauge is adjusted in the usual way by an indexed band running over band wheels indicated at 22, 23 for front and back, the operating construction not being shown.

To return the grid to its raised position, the trigger arm is formed with an extended surface 17a and so inclined that when the leveler is on the paper, the surface 17a will still lie in the path way of the roller 17 on the gear 18 in position to be returned to normal. It will be understood that the construction as shown is designed for low piles of paper and that therefore the full throw of the trigger arm 16 will not be sufficient to remove it from the path of the roller 17.

Having thus described my invention what I claim as new and desire to secure by Letters Patent is:—

- 25 1. In combination with a table and means for clamping paper thereon adjacent an edge of the paper to be cut, a pressure frame and means for suspending same in horizontal alignment with the table, and for imparting 30 parallel movement to said frame with relation to the table, a trigger arm secured to said means for holding the frame in suspended position and means operated by the clamp operating mechanism to release said trigger arm ahead of the engagement of the clamping means with the paper, for the purpose described.
- 35 2. In combination with a table and clamp operating mechanism, a pressure frame, bell crank levers mounted on the table, to which said pressure frame is secured, with links connecting said levers, an operating shaft with an arm connected to the bell crank levers, a trigger arm mounted on said shaft and means 40 operated by the clamp operating mechanism to release said trigger arm in timed relation to the clamp movement.
- 45 3. In combination with a table and means for clamping paper thereon adjacent an edge of the paper to be cut of a pressure frame, means for supporting the frame above the table and mechanism intermediate the supporting means and the clamp operating mechanism to release the frame supporting 50 devices ahead of engagement of the clamping means with the paper, said frame being shaped and located so as to cover that portion of the paper away from the edge to be clamped and cut.
- 55 60 4. In combination with a table and a clamp with clamp operating mechanism of a supplemental clamp member, comprising a metallic grid, a lever for supporting the grid above the table and a rotatable member with 65 roller to contact with said lever, with mecha-

nism intermediate said rotatable member and the clamp operating mechanism whereby said lever may be released in timed relation to the clamp movements.

5. In combination with a table and clamp operating mechanism, a pressure frame with bell crank levers provided with rollers mounted to ride horizontally on the table, boxes secured to the pressure frame with vertical guide ways on the table for said boxes, links connecting said bell cranks, an operating shaft with an arm connected to the bell crank levers, a trigger arm mounted on said shaft and means operated by the clamp operating mechanism to release said trigger arm in timed relation to the clamp movement.

6. In a paper cutting machine, a bed, and a clamp to engage a pile of paper on the bed adjacent to an edge to be cut, of means comprising a plurality of bars for smoothing out the pile of paper on the bed, and an operating device for the clamp and said plurality of bars arranged and timed to smooth the bundle and retain it in smooth condition during the operation of the clamp.
